US00D914272S

(12) **United States Design Patent** (10) **Patent No.:** **US D914,272 S**
Bramley et al. (45) **Date of Patent:** **** Mar. 23, 2021**

(54) **SMOKING ARTICLE**(71) Applicant: **Altria Client Services LLC**,
Richmond, VA (US)(72) Inventors: **Alistair Bramley**, Richmond, VA (US);
George Stafford, Richmond, VA (US);
Eric Hawes, Glen Allen, VA (US);
Traci Martin, Richmond, VA (US);
Berina Yerkic-Husejnovic, Richmond,
VA (US)(73) Assignee: **Altria Client Services LLC**,
Richmond, VA (US)(**) Term: **15 Years**(21) Appl. No.: **29/639,721**(22) Filed: **Mar. 8, 2018****Related U.S. Application Data**(62) Division of application No. 29/562,751, filed on Apr.
28, 2016, now Pat. No. Des. 815,340, which is a
division of application No. 29/471,454, filed on Oct.
31, 2013, now Pat. No. Des. 763,503.(51) **LOC (13) Cl.** **27-01**(52) **U.S. Cl.**USPC ..... **D27/101**(58) **Field of Classification Search**USPC D27/101, 162-167
CPC A24F 7/00; A24F 7/02; A24F 7/04; A24F
13/10; A24F 47/002

Primary Examiner — Janice Hallmark(74) *Attorney, Agent, or Firm* — Harness, Dickey &
Pierce, P.L.C.(57) **CLAIM**The ornamental design for a smoking article, as shown and
described.**DESCRIPTION**FIG. 1 is a perspective view of a smoking article showing
our new design.

FIG. 2 is a side elevational view thereof; and,

FIG. 3 is a right end elevational view thereof.

The broken lines showing portions of the smoking article are
for illustrative purposes only and form no part of the claimed
design.**1 Claim, 2 Drawing Sheets**| (56)	References Cited
